UNITED STATES PATENT OFFICE.

CAREY W. THOMPSON AND HENRY C. BEELER, OF DENVER, COLORADO.

PROCESS FOR CRACKING OIL.

Application filed September 19, 1922. Serial No. 589,124.

To all whom it may concern:

Be it known that we, CAREY W. THOMPSON and HENRY C. BEELER, citizens of the United States, and residents of Denver, in 5 the county of Denver, in the State of Colorado, have invented certain new and useful Improvements in Processes for Cracking Oil, of which the following is a specification.

10 Our present invention relates to the cracking of oil, or the conversion of heavy oil into hydrocarbons of a lower boiling point.

The primary object of our invention is the provision of certain details by which 15 this conversion is effected with maximum efficiency.

The invention includes a device for conveying an inert carrier which has been mixed with the heavy oil to be converted, through 20 a retort which may be progressively heated in any preferred manner, to form zones of varying heat intensity. Said zone take-offs are provided for the removal of material vaporized in these zones, separately or in a 25 common duct, as may be found desirable. The heavy hydrocarbons liberated may be returned to the conveyor in proximity to the cold end and made to pass through the zones a second time in order to insure complete removal of the higher distillates. It 30 may be found desirable to provide in the take-offs mentioned, certain catalysts, which serve normally the purpose of increasing the saturation of the material acted on, by 35 providing a condensing, separating and re-vaporizing action most advantageous in this art.

In the drawing we have illustrated diagrammatically a satisfactory device for the 40 accomplishment of the desired objects, in which a hopper is illustrated at 1 adapted to contain the carrier material, which may be spent shale, gravel, or the like, delivering said material into a rotary or other conveyor 2, which is heated by means of fire chamber 3, fed from any desired source. A 45 delivery pipe 4 is provided for the heavy oil to be acted upon, which is delivered to the carrier at the cold end of the conveyor and becomes thoroughly mixed with the carrier in its travel through the retort. As the 50 material passes in the first heat zone cer-

tain low boiling point vapors are set free and may be removed through duct 5 for further treatment if desired. Continued rotation of the conveyor carries the material into the hotter zones where more hydrocarbons of a slightly higher boiling point, are liberated and which are adapted to be carried off through manifold 6 and duct 7 for further treatment. In the passage 55 through the manifold the gases will necessarily be slightly cooled, the more readily condensable vapors entering the conveyor through the port 8, from which the cycle 60 is repeated. It has been found desirable to provide the take-offs with a grid or the like 9, upon which is supported material 10, of a catalytic nature, such as pumice, volcanic ash, fuller's earth, and similar materials. In passing upwardly through this 65 material the vaporized hydrocarbons are cooled to a certain extent, the material 10 acting as a vapor baffle, thus retarding the flow from the retort and allowing 70 the condensation and separating out of the heavier hydrocarbons which are thus returned to the carrier material, where they are re-vaporized, more light hydrocarbon vapors formed, and the carbon set free as 75 a result of such action deposited on the carrier and continuing to the end of the conveyor. We are aware that these materials have been used as filtering mediums, and such we do not claim, it being distinctly 80 understood that such filtering action forms no part of this present invention. Due to the fact that the lighter the oil, the cooler the vapor may be without being condensed, whereas the heavier oils will condense at a 85 higher temperature than the escaping lighter oils, we are able, by the use of said material 10, to get a cleaner fraction and a more efficient conversion by condensing the heavier oils and returning the same to the 90 conveyor, thus causing them to pass through a hotter zone.

The carrier material, when it reaches the end of the conveyor, drops through conduit 11 into a second conveyor 12 from which it 100 may be elevated by a suitable device 13 to a bin 14, to be disposed of as expedient.

Having thus described our invention, what we claim is:—

A process of treating liquid hydrocarbons, which comprises the steps of subjecting a mixture of liquid hydrocarbons and an inert carrier to successive zones of increasing temperature, independently removing the lightest portion, independently re-fluxing within the heating zones the vapors formed at the successive zones of heating, and combining

the uncondensed vapors and further cooling said vapors and returning the condensate 10 so formed to the said mixture.

In testimony whereof, we affix our signatures.

CAREY W. THOMPSON.
HENRY C. BEELER.
